US00D573369S

(12) **United States Design Patent**
Sparkowski

(10) **Patent No.:** US D573,369 S
(45) **Date of Patent:** ** Jul. 22, 2008

(54) **MOVEABLE STAND-ALONE WIRE DISPLAY AND SHELVING UNIT**

(75) Inventor: **Robert P. Sparkowski**, Schaumburg, IL (US)

(73) Assignee: **Chicago Display Marketing Corporation**, River Grove, IL (US)

(**) Term: **14 Years**

(21) Appl. No.: **29/276,144**

(22) Filed: **Jan. 17, 2007**

(51) **LOC (8) Cl.** 06-04

(52) **U.S. Cl.** D6/463

(58) **Field of Classification Search** D6/468, D6/414, 436, 478, 467, 462, 396, 397, 479, D6/477, 466, 473; 211/59.4, 85.1, 135, 163, 211/69, 85.5, 85.2, 13.1, 153, 186-190, 194; 108/59, 91, 161, 111, 2, 108

See application file for complete search history.

(57) **CLAIM**

The ornamental design for a moveable stand-alone wire display shelving unit, as shown.

DESCRIPTION

FIG. 1 is a perspective view of the moveable stand-alone wire display shelving unit.

FIG. 2 is a front view of the moveable stand-alone wire display shelving unit.

FIG. 3 is a rear view of the moveable stand-alone wire display shelving unit.

FIG. 4 is a left side view of the moveable stand-alone wire display shelving unit.

FIG. 5 is a right side view of the moveable stand-alone wire display shelving unit.

FIG. 6 is a top plan view of the moveable stand-alone wire display shelving unit; and,

FIG. 7 is a bottom plan view of the moveable stand-alone wire display shelving unit.

1 Claim, 4 Drawing Sheets
